UNITED STATES PATENT OFFICE.

WILLIAM C. HORNER, OF INDIANAPOLIS, INDIANA, ASSIGNOR TO
CHARLES P. McDougall, OF INDIANAPOLIS, INDIANA.

KITCHEN-CABINET.

No. 824,864.

Specification of Letters Patent.

Patented July 3, 1906.

Application filed October 7, 1905. Serial No. 281,849.

To all whom it may concern:

Be it known that I, WILLIAM C. HORNER, a citizen of the United States, residing at Indianapolis, in the county of Marion and State 5 of Indiana, have invented certain new and useful Improvements in Kitchen-Cabinets, of which the following is a specification.

The object of my invention is to produce a cabinet (especially designed for the base of a kitchen-cabinet) in which there shall be embodied a swinging bin, the exposed portion of said bin having the general appearance of a drawer-front and so arranged that swinging doors forming a closure for the main portion 15 of the base of the cabinet may be swung beneath the bin-front to hide the lower portion of the bin and to prevent said bin from being swung outward to open position until after the swinging doors have been opened.

20 The accompanying drawings illustrate my invention.

Figure 1 is a front elevation of a cabinet embodying my invention with the bin and swinging doors in closed position; Fig. 2, a 25 similar view showing the swinging doors opened, and Fig. 3 a section on line 3 3 of Fig. 1.

In the drawings, 10 indicates a box-like base having a table-top 11 and an open front 30. Within the casing 10 I arrange hangers 13, connected at their bottoms by a cross-bar 14, upon which is pivotally supported by crotch-brackets 15 a swinging bin 16, having a projecting front 17 in the simulation of an ordinary drawer-front which overlaps the hangers 13, as at 17', in order to limit the closing 35 movement of the bin.

In the drawings I show the bin flanked at each side by a drawer 18; but these may be 40 omitted, if desired, and the bin may be supported by any suitable means other than that shown. That portion of the open front of the casing 10 beneath the drawers 18 and the portion 17 of the bin 16 is closed by a pair 45 of swinging doors 19-19, hinged at their edges to the front corner-posts of the casing 10, and said doors 19 are of such height as to swing

under the bin-front 17, so as to cover the main lower portion of the bin from sight and so as to prevent any downward and outward 50 swing of the bin so long as the doors remain closed. By this construction and arrangement I am able to prevent accidental opening of the bin and am also able to disguise the appearance of the bin when the cabinet is 55 closed, thus eliminating an objectionable appearance of the structure.

I claim as my invention—

1. The combination, with a suitable inclosing casing having an open front, of a bin 60 movably mounted in said casing and having a projecting front finishing plate 17, and a closure for the open front of the casing arranged to lie beneath said finishing-plate when closed. 65

2. The combination, with a suitable inclosing casing having an open front, of a bin movably mounted in said casing and having a projecting portion, a closure adapted to close the open front of the casing and, when 70 closed, to lie under the projecting portion of the brain.

3. The combination, with a suitable inclosing casing having an open front, of a bin structure pivotally mounted therein and provided at its upper forward end with a finish-plate, and a swinging closure adapted to close the open face of the casing and swing 75 beneath said finish-plate.

4. The combination, with a suitable inclos- 80 ing casing having an open front, of a bin structure pivotally mounted therein and provided at its upper forward end with a projecting finish-plate, and a pair of swinging doors hinged at the opposite sides of the cas- 85 ing-opening and adapted to swing beneath the finish-plate when the bin is closed.

In witness whereof I have hereunto set my hand and seal, at Indianapolis, Indiana, this 27th day of September, A. D. 1905

WILLIAM C. HORNER. [L. S.]

Witnesses:

ARTHUR M. HOOD,
JAMES A. WALSH.
